UNITED STATES PATENT OFFICE.

CHARLES H. MORSE, OF ROCHESTER, NEW YORK.

DESIGN FOR COAL-SCUTTLE.

Specification forming part of Design No. **7,961**, dated December 29, 1874; application filed November 28, 1874.
[Term of Patent 7 years.]

To all whom it may concern:

Be it known that I, CHARLES H. MORSE, of the city of Rochester, in the county of Monroe and State of New York, have invented a new and original Design for Coal-Hods; and I do hereby declare that the following is a full, clear, and exact description of the same, reference being had to the accompanying drawings, in which--

Figure 1 is a perspective view. Fig. 2 is a plan.

My invention relates especially to the configuration of the side edges of the spout, as hereinafter described.

A is the hod. B is the spout, and $a a$ are the flanges of the same. The front edge of the spout is square, as shown at b , or curved. In elevation, Fig. 1, the front edges of the flanges from x to x^1 are segments of a true circle, which leave the swell of the flanges directly at the front end of the spout. The rear edges from x^1 to x^2 are plane or straight. In plan view, Fig. 2, the edges from x to x^1 are par-

allel with the major axis of the hod, and from x^1 to x^2 are concave.

These flanges differ from those of ordinary hods in the above-described configuration, being segments of a true circle in front, and straight in the rear, and presenting a combined plane and concave outline in plan. This presents an ornamental appearance, the swells of the flanges being at the extreme front, whereas in ordinary hods the form is reversed, the planes coming in front, and the swells at the rear near the ears.

I claim—

The design for a coal-hod consisting of the parallel flanges $a a$, the edges made segments of a true circle in front and straight in the rear, as herein shown and described.

In witness whereof I have hereunto signed my name in the presence of two subscribing witnesses.

Witnesses:

FRED. A. HATCH,
R. F. OSGOOD.
